GRAIN PLANTER

Filed Jan. 9, 1930

UNITED STATES PATENT OFFICE

MICHEL F. SCHOU, OF KALAMAZOO, MICHIGAN, ASSIGNOR OF ONE-HALF TO MARY MAZUR, OF KALAMAZOO, MICHIGAN

GRAIN PLANTER

Application filed January 9, 1930. Serial No. 419,504.

The main object of this invention is to provide in a grain planter an improved dropping mechanism whereby grain such as corn may be accurately dropped in spaced relation.

5 A further object is to provide a dropping mechanism which may be applied as an attachment to the check-row type of planters or may be readily built into or incorporated in such type of planters.

10 Objects relating to details and economies of my invention will appear from the description to follow. The invention is defined and pointed out in the claims.

15 A structure which is a preferred embodiment of my invention is illustrated in the accompanying drawings, in which:

Fig. 1 is a fragmentary vertical view partially in vertical section of a planter embodying the features of my invention, the parts of 20 my attachment or improvements being indicated in full lines, the remaining portions being illustrated by dotted lines.

Fig. 2 is a fragmentary plan view of parts of my invention.

25 Fig. 3 is a fragmentary view partially in section on line 3-3 of Fig. 2.

Fig. 4 is a fragmentary view showing the dropping mechanism in inoperative relation, partially sectioned on line 4-4 of Fig. 2.

30 Referring to the drawings, 1 represents one of the carrying and driving wheels and 2 the driven axle.

The furrow opener or shoe 3 is mounted on a frame 4 extending forwardly from the axle.

35 The hopper 5 is associated with a feed mechanism designated generally by the numeral 6. As this feed mechanism and details of the shoe form no part of my invention, they are not detailed herein.

40 The dropping mechanism is provided with an arm 7 mounted on the side of the shoe or boot 8, the dropping mechanism being housed within this boot.

45 The dropping control rockshaft 9 is connected by the parts 10 to this arm 7 so that as the rockshaft is oscillated, the dropper is actuated. These particular details also are not illustrated as they form no part of this invention.

50 The rockshaft 9 is provided with an up-

wardly projecting arm 11 which is connected by the link 12 to one arm of the bell crank lever 13. The link 12 is longitudinally slotted at 14 to receive the pin 15 on the lever.

A thrust block 16 is pivotally mounted at 17 on the end of the link so that it may be swung down into abutting relation to the lever, thereby locking the pin 15 in the end of the slot and connecting the lever to the link so that as the lever is oscillated its movement is imparted to the link. When the thrust block is swung to inoperative position shown in Fig. 4, the lever may oscillate without imparting its motion to the link.

The lever is mounted on a pivot 18 between the arms 19 of the bifurcated bracket 20. This bracket is provided with bearing members 21 coacting with the axle and supporting the rear end of the bracket.

A cam 22 is rotatably and slidably mounted on the axle between the arms of the bracket to coact with the actuating lever. This cam is provided with a clutch member 23 coacting with the clutch member 24 pinned to the axle.

The shifting lever 25 is mounted on the axle and provided with a cam 26 coacting with a cam 27 on one of the bracket bearing members so that when the lever 25 is shifted to one position the clutch members are engaged and held in engagement, and when shifted to releasing position the coiled spring 28 arranged between the clutch members acts to disengage them—see Fig. 3.

A spring 29 connected to the lever 13 above its pivot and to the bracket acts to hold the lever in coacting relation to the cam.

The front end of the bracket is supported by the bar 30 which is mounted at its front end on the rockshaft 9, the rear end being slidably or telescopingly engaged with the front end of the bracket which is provided with a longitudinal pocket or holder for the rear end of the bar. This permits the raising and lowering of the furrow opener and the parts moving with it.

My improvements are readily embodied in machines of the check-row type either as attachments or incorporated as the machine is built.

I have shown only such parts of the mecha-

nism as seen essential to a proper understanding thereof and have not attempted to illustrate various embodiments and adaptations which might be desirable to adapt to machines of particular makers.

5 Having thus described my invention, what I claim as new and desire to secure by Letters Patent, is:

1. The combination in a planter including 10 a dropping mechanism and carrying and driving wheels provided with an axle, of a dropping mechanism actuating rockshaft operatively connected with the dropping mechanism, an arm on said rockshaft, a bell 15 crank actuating lever, a link pivoted to said arm on said rockshaft and having a slot therein, said actuating lever being provided with a pin engaging said slot, a thrust member pivotally mounted on said link and 20 adapted when swung to one position to hold the pin in engagement with the end of the slot whereby a movement of the actuating lever is imparted to the rockshaft and in another position to permit movement of the 25 lever without actuating said rockshaft, a cam on said axle coacting with said actuating lever, a return spring for said lever, and a clutch for detachably connecting said cam to said axle.
- 30 2. The combination in a planter including a dropping mechanism and carrying and driving wheels provided with an axle, of a dropping mechanism actuating rockshaft operatively connected with the dropping mechanism, an arm on said rockshaft, a bell crank 35 actuating lever, a link pivoted to said arm on said rockshaft and having a slot therein, said actuating lever being provided with a pin engaging said slot, a thrust member pivotally mounted on said link and adapted when 40 swung to one position to hold the pin in engagement with the end of the slot whereby a movement of the actuating lever is imparted to the rockshaft and in another position to 45 permit movement of the lever without actuating said rockshaft, and a cam on said axle coacting with said actuating lever.

3. The combination in a planter including 50 a dropping mechanism and carrying and driving wheels provided with a driven axle, of a rockshaft operatively associated with said dropping mechanism and provided with an arm, a bifurcated supporting bracket having bearing members coacting with said axle for 55 supporting the bracket at one end, one of said bracket bearing members having a cam thereon, a supporting bar for the front end of said bracket mounted on said rockshaft and having sliding engagement with the forward end 60 of said bracket, an actuating lever pivotally mounted on said bracket between its arms, a link connecting said actuating lever to said arm on said rockshaft, a cam rotatably and slidably mounted on said axle between the 65 arms of said bracket and provided with a

clutch member, a coacting clutch member fixed to said axle, a spring between said clutch members acting to disengage the same, a shifting lever provided with a cam coacting with the cam on said bracket whereby said clutch members are actuated to and retained in engagement, and a spring acting to hold said actuating lever in engagement with said cam.

4. The combination in a planter including 75 a dropping mechanism and carrying and driving wheels provided with a driven axle, of a rock shaft operatively associated with said dropping mechanism and provided with an arm, a bifurcated supporting bracket having bearing members coacting with said axle for supporting the bracket at one end, a supporting bar for the front end of said bracket mounted on said rockshaft and having sliding engagement with the forward end of said bracket, an actuating lever pivotally mounted on said bracket between its arms, a link connecting said actuating lever to said arm on said rockshaft, a cam rotatably mounted on said axle between the arms of said bracket, a clutch for connecting said cam to said axle, and a spring acting to hold said actuating lever in engagement with said cam.

5. The combination in a planter including 95 a dropping mechanism and carrying and driving wheels provided with a driven axle, of a rock shaft operatively associated with said dropping mechanism and provided with an arm, a supporting bracket having a bearing member coacting with said axle for supporting the bracket at one end, a supporting bar for the front end of said bracket mounted on said rockshaft, an actuating lever pivotally mounted on said bracket, a link connecting said actuating lever to said arm on said rockshaft, a cam on said axle, and a spring acting 100 to hold said actuating lever in engagement with said cam.

In witness whereof I have hereunto set my hand.

MICHEL F. SCHOU.
